UNITED STATES PATENT OFFICE.

HARRY SISKIN, OF LOS ANGELES, CALIFORNIA.

UPHOLSTERY EDGE.

Application filed January 15, 1924. Serial No. 686,248.

To all whom it may concern:

Be it known that I, HARRY SISKIN, a citizen of the United States, residing at Los Angeles, in the county of Los Angeles and State of California, have invented new and useful Improvements in Upholstery Edges, of which the following is a specification.

My present invention being entitled as referring to an upholstery edge, it may be understood to be an object of this invention to provide a novel edge construction suitable for use upon "over-stuffed" furniture, or the like, and to provide a method for the production of edges upon furniture of the general character referred to.

It is an object of this invention to provide "over-stuffed" furniture, or the like, with edge rolls not liable to deterioration but of especially simple and rugged construction; and my invention comprises also an advantageous method of assembling and associating the materials comprised in an edge roll, mainly in advance of the application of the same to articles of furniture; and it is an especial merit of my novel method of assembling the mentioned elements, which may comprise a core element covered with felt and retained by stitching, that a large part of the stitching that has heretofore been done mainly by hand, may, by my improved method, be done by machinery and in advance of the actual positioning of the assembled materials upon an article of furniture.

As implied above, it is an object of my invention to provide means whereby articles of furniture may be provided with edge rolls more economically and expeditiously than heretofore, the materials employed being of any desired grade but not necessarily more costly than those in current use.

Other objects of my invention will appear from the following description of advantageous embodiments thereof, and from the appended claims, taken in connection with the accompanying drawings, in which,

Fig. 1 is a perspective representation of one article of furniture, to-wit, a rocker, of the "over-stuffed" type, in connection with which my invention may be employed to a special advantage, this rocker being shown as without the removable box springs customarily provided therefor, and without a cushion.

Fig. 2 is a perspective representation of

a box spring of the type suitable for use in an "over-stuffed" article of furniture such as is shown in Fig. 1.

Fig. 3 is a perspective view showing a preferred mode of construction of a box spring of the type illustrated in Fig. 2, assuming the covering materials therefor to have been previously stitched together in a manner hereinafter referred to.

Figs. 4 and 5 are perspective illustrations respectively of felt and core materials suitable for employment in a rolled edge, in a manner illustrated in the succeeding figures.

Figs. 6 and 7 are perspective views illustrating successive steps in the assembling and securing of the materials illustrated in Figs. 4 and 5 in connection with lining materials and cover materials and stuffing or filling materials secured thereto, preferably by machine stitching executed by comparatively unskilled labor in advance of the adjustment of the same upon the springs or frame of an article of furniture.

Figs. 8 and 9 are respectively a sectional perspective and a vertical section illustrating subsequent steps in the production of an upholstery edge and a stuffed top upon a box spring of the general character illustrated in Figs. 2 and 3.

Fig. 10 is a horizontal sectional view which may be regarded as taken on the line 10—10 of Fig. 1, this view illustrating an advantageous method of securing edge roll adjacent an unyielding edge of an article of furniture.

Referring to the details of that specific embodiment of my invention illustrated in Figs. 2—9 inclusive, 1 being a frame upon which a box seat is to be built, and 2 being springs supported therefrom by means of metallic or other strips 3 provided with clips 4 and retained by nails or screws 5, the tops of the springs 2 being retained in their intended relationship by means of an iron or other frame 6, and all of the parts thus referred to being of any usual or preferred construction immaterial to the present invention, 7 may be a core formed of twisted paper or other suitable material, and 8 may be a suitably cut section of felt adapted to be rolled thereover in the manner suggested in Figs. 4 and 6.

Instead of employing a stitching, or the like, merely to hold the felt 8 upon the core 7, or its equivalent, I consider it advantageous to place in contact to the folded

edges of the felt, as shown in Fig. 6, the interior surface of a suitably cut and refolded section of cover material 9, the refolded edge 10 of this material being placed 5 substantially parallel with the edges 11, 11' of the felt 8, in a manner permitting the simultaneous stitching of the mentioned elements, optionally associated also with the burlap or other lining element 12, by 10 a single row of stitching 13, such as may be effected by a sewing machine run by a comparatively unskilled operative.

As will be seen, for example, Figure 7, the stitching 13 extends through intermediate 15 portions, and not through end portions of the cover material 9 and the lining material 12, both of which should, however, have been previously cut into a form suitable to an intended use, the end 9^a of the 20 cover material being, in case the same is to be used upon a box seat of the general character shown in Fig. 1, of sufficient length to provide not only for the covering of the roll 14, produced by folding the felt 25 8 over the core 7 as described, but of sufficient length to provide also, after attachment, as by a seam 15, to a section of denim or other inexpensive cover material 16, to permit of an additional row of stitching 17, effected either before or after the 30 application of the assembled elements to an article of furniture, in a manner serving not only completely to enclose the roll 14 but also securely to retain the same in an 35 intended relationship to a resilient or rigid corner upon which the same may be applied.

Either before or after the attachment, as by means of stitching 17, of what I may 40 term a fin 18, produced by folding or by securing adjacent ends of cover fabrics by means such as the stitching 15, I may secure the burlap lining 12, or its equivalent, through which the stitching 13 extends, to 45 the frame 6, or its equivalent, comprised in a box spring, threads or cords 19, or their equivalent, being employed to secure the roll 14, covered in the manner described, in a desired relationship to an edge element 50 20 of said frame; and I may thereafter secure the end 9^b of the cover material 9, to the lower frame 1 of a box spring, stretching the described materials thereover to produce a desired tension and retaining 55 them by any suitable means such as the tacks 21. As is suggested in Figs. 6, 7 and 8, the burlap or other lining material 12 may advantageously extend not only across the horizontal top of a box seat of the character herein referred to but also over the front surface thereof in the manner suggested, at 12^b; and either before or after the securing of the end 9^b of the cover material and the end 12^b of the lining material 60 65 by means such as the tacks 21, I may

optionally interpose stuffing material 22, retaining the same in any suitable manner, as by means of stitching 23, shown as extending through both the mentioned cover material and the mentioned lining material, the stitching here referred to, like that mentioned above, being optionally done in advance of the positioning of the fabric elements, secured together as described, 70 upon the frame 6 of the box spring. 75

Having secured the fabric elements mentioned to one another by stitching in the economical and comparatively inexpensive manner referred to and having secured the materials so assembled to the top and bottom frames of a box spring in the manner described, I may advantageously proceed with the insertion of additional filling or stuffing material 24, interposed between the horizontally extending portion 12^a of the 80 burlap lining referred to and the denim or other cover material 16 adapted to cooperate therewith in the retention of said stuffing or filling material, and the corresponding free end of the burlap lining, these elements being optionally stitched or otherwise secured together, as along the line 25 at the upper rear edge of a box spring, and thereafter secured, as by tacking along the lower rear edge, to the frame 1. 90 95

When my novel upholstery edge is to be applied to a rigid rather than to a yielding edge, the general procedure outlined above may optionally be employed except that, 100 when it is desired that a rolled edge and the outer and inner surface of an article of furniture shall be covered by a continuous expanse of uniform material uninterrupted by any crease or seam, as is considered appropriate in the covering of the arms of a 105 rocker, or the like, in the manner illustrated in Figs. 1 and 10, no effort need be made to provide a fin such as is shown at 18, or its equivalent, or to secure such a fin to a burlap or other lining. In the application of my invention which is somewhat 110 diagrammatically illustrated in Fig. 10, 26 being an upright wooden element employed at the front of an arm, and 27 being an outside frame element associated therewith, 115 14' may be an edge roll secured to a fold 10' in cover material 9' by means of stitching 13', this stitching being preferably carried also through a lining material 12', and the end 9^{a'} of the mentioned covering material may extend smoothly and continuously over the stuffing or filling material 24' the opposite end 9^{b'} of said covering material being secured in any suitable way, 120 as by means of tacks 21' shown as extending therethrough and also through a refolded end or edge of a separate section of covering material 28, employed upon the outer side of the arm referred to. 125

Although I have herein described alter- 130

native complete embodiments of my invention, as the same may be employed in the providing of rolled edges upon over-stuffed furniture or the like, it should be understood that various features of my invention may be independently employed and also that various additional modifications might be made therein by those skilled in the art without the slightest departure from the spirit and scope of my invention as the same is indicated above and in the following claims.

It is to be understood that in place of felt, any equivalent resilient material may be used in place of it and the term "felt" in the claims is to be understood to include equivalents.

What I claim is:

1. In an article of furniture, a core, a sheet of felt folded over the core, a cover having a refolded edge fitting under the felt, the cover extending from the refolded edge around the felt, a lining under the refolded edge, stitching through the felt, refolded edge and lining, and stitching connecting the opposite edge of the cover from the refolded edge to the lining.

2. In an article of furniture, an upholstery edge comprising a core, a sheet of felt folded around the core, a lining, a cover

having a refolded edge extending under the felt against the lining, stitching connecting the felt, refolded edge and lining, the cover material extending from the refolded edge around the felt and stitched to the lining, a second cover material stitched to the first cover material behind the felt and a filling between the lining and second cover material.

3. In an article of furniture, the combination with a base and a coil-spring supporting frame having a wire edge, of a lining secured to the base and extending over the wire edge and resting upon the top of the coil spring construction, a cover secured to the base through the lining and having a refolded edge fitting over the lining above the wire edge, a core, a sheet of felt folded around the core with the edges flat together and extending inwardly, the cover material extending outwardly and upwardly around the felt, a second cover material secured to the inner edge of the first cover material and forming a fin, stitching securing the edge of the fin to the lining, and filling between the second cover material and lining.

In testimony whereof I have signed my name to this specification.

HARRY SISKIN.
